UNITED STATES PATENT OFFICE.

CHARLES F. MERRILL, OF HOPEDALE, MASSACHUSETTS, ASSIGNOR TO DRAPER CORPORATION, OF HOPEDALE, MASSACHUSETTS, A CORPORATION OF MAINE.

SPINNING RING AND TRAVELER.

Application filed February 18, 1927. Serial No. 169,350.

This invention relates to the cooperating ring and traveler elements of ring spinning mechanism employed in the spinning and twisting of yarns. The invention relates particularly to that type of ring and traveler, such, for example, as disclosed in my prior Patent, No. 1,604,929, granted October 26, 1926, in which the yarn during the spinning operation extends between, is pressed between, and forms a bearing medium between the traveler and the surface of the ring upon which the traveler is revolving.

In this type of mechanism the bearing pressure of the traveler, due to centrifugal force and to gravity, is taken in part by the interposed yarn and in part directly by the ring surface. Under some conditions the relative division of this pressure may be such as to interrupt the continuity of the spinning process. If, for example, the pressure of the traveler against the interposed yarn forming the bearing medium between the traveler and the ring surface is relatively great, while the frictional resistance between the traveler and that portion of the ring surface with which it directly contacts is relatively small, the passage of the yarn through the traveler may be restricted or entirely interrupted. If and when this happens, the traveler will revolve on the ring at the same, or nearly the same, speed of revolution as that of the yarn receiver or bobbin and the yarn will not be wound up.

It is obviously essential that the fibres or yarns delivered to the traveler and spun or twisted together shall pass through the traveler in order to be wound upon the bobbin or yarn receiver.

The main object of the present invention is to insure such passage of the yarn through the traveler as is necessary for the winding of the spun or twisted yarn on the bobbin or yarn receiver in conjunction with that type of spinning mechanism wherein the yarn is normally pressed between the cooperating opposed traveler and ring surfaces.

The present invention is based upon the principle that the required passage of the yarn through the traveler, while it must take place during each revolution of the traveler, need not take place uniformly and continuously throughout the entire revolution but may take place at one or more por-

tions of the revolution. This is due to the fact that the amount of yarn to be wound on the bobbin at each revolution is relatively small, being approximately equal to the reciprocal of the number of turns of twist per inch. For example, if the yarn being spun has twenty-eight turns of twist per inch, there will be approximately one twenty-eighth of an inch of yarn delivered to the bobbin at each revolution thereof.

If, then, there is an opportunity at some point in the revolution of the traveler for the yarn to pass freely through the traveler for a sufficient time to allow this small amount to advance toward the bobbin, it follows that the advance of the yarn through the traveler may be entirely stopped during the remaining portion of the revolution.

The object of the invention more specifically is to secure the desired result by forming a depression in the bearing surface of the ring against which the yarn is normally carried by the traveler, so that as the traveler passes over this depression, the bearing pressure on the yarn will be relieved and the yarn thus released for winding.

These and other objects and features of the invention will appear more fully from the accompanying description and drawings and will be particularly pointed out in the claims.

Since the operation of ring spinning and the various mechanisms employed for performing this operation are well known and familiar to those skilled in the art, and since the aforesaid Patent No. 1,604,929 sets forth quite fully the conditions existing in that type wherein the yarn forms a bearing medium between opposed cooperating surfaces of the ring and traveler during the spinning operation, it is only necessary here to illustrate and describe the preferred features of construction and their operation in which the present invention may be embodied.

In the drawings:

Fig. 1 represents a detail partially in vertical cross section and much enlarged showing a portion of a bobbin, a ring and a traveler embodying a preferred form of the present invention and in the relation existing when in a spinning frame.

Fig. 2 is a top plan view of the construction shown in Fig. 1.

Fig. 3 is a view similar to a portion of Fig. 1 showing a second form of the invention.

Fig. 4 is a top plan view of the construction shown in Fig. 3.

Fig. 5 is a view similar to Fig. 1 of a third form of the invention.

Fig. 6 is a top plan view of the construction shown in Fig. 5.

Fig. 7 is a view similar to Fig. 3 showing a fourth form of the invention.

Fig. 8 is a top plan view of the construction shown in Fig. 7.

Fig. 9 is a view similar to Fig. 1 omitting the bobbin and showing a fifth form of the invention wherein the ring is of the vertical type such as employed in a twister frame.

Fig. 10 is a top plan view of the construction shown in Fig. 9.

Fig. 11 is a view similar to a portion of Fig. 9 showing a sixth form of the invention.

Fig. 12 is a top plan view of the construction shown in Fig. 11.

In the operation of ring spinning the yarn passes down through a guide eye and thence through the traveler and thence to the bobbin or other yarn receiver upon which it is wound. A relative, vertical movement is given to the yarn and yarn receiver to secure the traverse of the yarn lengthwise of the yarn receiver.

As already pointed out, the present invention has to do with that type of ring spinning mechanism wherein the yarn extends between, is pressed between and forms a bearing medium between the traveler and the surface of the ring. Consequently so long as this relation exists during the normal spinning operation, the ring and traveler may take a wide variety of shapes. In Figs. 1, 2, 5 and 6 of the drawings, the ring and traveler are similar to constructions illustrated in the aforesaid Patent No. 1,604,929; in Figs. 3, 4, 7 and 8 the traveler is shown as of the old and familiar C-shape, while the ring surface is shaped to embody in connection with this old type of traveler the basic principles of the aforesaid Patent No. 1,604,929; and in Figs. 9 to 12, inclusive, the ring and traveler are shown as of the vertical type, such as more commonly employed in twisting.

In the construction illustrated in Figs. 1 and 2, the yarn 1 is shown passing down through the traveler and being wound upon a bobbin or yarn receiver 2. The ring 3 and traveler 4 are shown constructed in accordance with the principles of the aforesaid Patent No. 1,604,929. The portion of the flange 5 of the ring which is traversed by the traveler is shaped in a general way to correspond with the shape of the traveler, and the inner, upper, peripheral surface 6 and the inner, lower, peripheral surface 7 both converge inwardly. The traveler,

which may be formed of the usual stock of which travelers are made, is preferably a symmetrical structure presenting a central bow section 8 of substantially circular arcuate form, the sides of which merge by smooth curves into the horns 9. With this construction, during the normal spinning operation, one horn 9 of the traveler has an extended bearing throughout its length upon the inner, lower, peripheral surface 7 of the ring, while the adjacent section of the bow 8 presents substantially the same angular relation to the horn 9 as does the upper, peripheral surface 6 to the lower, peripheral surface 7 of the ring. Under these conditions the adjacent section of the traveler extends substantially equidistant from or in a general way parallel with, the upper, inner bearing surface 6 of the ring and the yarn extends between and is pressed between and forms a bearing medium between these two cooperating opposed surfaces, that is, the inner surface of the bow section of the traveler and the inner, upper, peripheral surface 6 of the ring.

If, then, owing to the relative frictional conditions existing and the forces acting, particularly the centrifugal force generated by the revolution of the traveler and the force of gravity, the yarn does not pass through the traveler as required for winding upon the bobbin in the spinning operation, the traveler and the bobbin will revolve in unison, as already pointed out, and the spinning operation will be interfered with and interrupted.

In the construction shown in Figs. 1 and 2, a depression, herein shown as a groove 10, is formed in that surface of the ring over which the yarn is carried by the traveler and which in this case is the upper, inner peripheral surface 6. When, therefore, the traveler passes over this groove, the bearing pressure on the yarn is momentarily relieved and thus the yarn is released sufficiently to allow its passage through the traveler to be wound on the bobbin 2. As already pointed out, but a very small length of yarn is thus wound at each revolution of the traveler and hence the groove 10 may be relatively narrow. But the width or the number of these depressions or grooves employed may obviously be varied as required.

The groove 10 also preferably extends at an inclination to the elements of the surface 6 and also at an inclination to the plane of the traveler when running. This is desirable because it prevents the traveler when passing over the groove from dropping into the groove or below the bearing surface of the ring.

The construction shown in Figs. 3 and 4 is similar to that just described, except as to the particular shape of the ring and

traveler. In these figures the traveler 11 is of the old style or C-shape where the horns 12 extend toward each other. By shaping the flange 13 of the ring substantially as shown, this shape of traveler may be made to run with its inner horn 12 having an extended bearing on the lower, inner, peripheral surface 14 of the ring, while the adjacent portion of the bow section and the upper, inner, peripheral surface 15 of the ring are opposed and cooperate with the yarn extending between them, pressed between them and forming a bearing medium between them during the normal spinning operation. With this construction, utilizing the old style traveler, the traveler will run in a tilted position, as shown, to allow the proper cooperation of the various bearing surfaces. The inner, peripheral surfaces 14 and 15 of the ring converge inwardly.

In this construction the depression or groove 16 is constructed upon the same principle and has the same functions as that shown at 10 in the preceding figures.

The construction shown in Figs. 5 and 6 is the same as that shown in Figs. 1 and 2 except that the depression provided for relieving the bearing pressure on the yarn during a portion of each revolution of the traveler to release the yarn for winding is of a different form. Here this depression 17 is as if made with a cylindrical cutter having its axis radial to the axis of the ring. In practice it is found that such a depression may be used of sufficient length to relieve the bearing pressure on the yarn to the required extent without chattering of the traveler.

The construction shown in Figs. 7 and 8 is the same as that shown in Figs. 3 and 4 except that the depression 18 is of the same form as the depression 17 shown in Figs. 5 and 6.

In the construction shown in Figs. 9 to 12, inclusive, the ring 19 is of the vertical type. In this case the traveler 20 has a portion, or the whole, of its inner vertical surface extending substantially parallel to the inner peripheral surface 21 of the ring so that these opposed surfaces of the traveler and ring under the forces acting press against the yarn extending between them and here likewise the yarn forms a bearing medium between the traveler and ring. In Figs. 9 and 10 a depression in the form of a groove 22 extends at an inclination across the peripheral surface 21 of the ring or that portion thereof over which the yarn 23 is carried by the traveler, while in Figs. 11 and 12 the depression 24 for the same purpose is not inclined, but is of greater width. These two constructions serve to illustrate the application of the principles of this invention to a vertical type of ring wherein the yarn

extends between opposed cooperating surfaces of the traveler and ring and forms a bearing medium therebetween. The groove 22 or the depression 24 will in either case relieve the bearing pressure on the yarn during a portion of each revolution of the traveler and thus release the requisite amount of yarn for winding on the bobbin or yarn receiver.

Having thus described the invention, what is claimed as new, and desired to be secured by Letters Patent, is:

1. A spinning mechanism comprising a spinning ring and a traveler having opposed cooperating surfaces between which the yarn extends and is pressed and forms a bearing medium during the spinning operation, the said ring surface having a depression for relieving the bearing pressure on the yarn during a portion of each revolution of the traveler to release the yarn for winding.

2. A spinning mechanism comprising a spinning ring and a traveler having opposed cooperating surfaces between which the yarn extends and is pressed and forms a bearing medium during the spinning operation, the said ring surface having a groove extending thereacross at an inclination to the elements thereof for relieving the bearing pressure on the yarn during a portion of each revolution of the traveler to release the yarn for winding.

3. A spinning mechanism comprising the construction defined in claim 2, in which the said groove also extends at an inclination to the plane of the traveler when running to prevent the traveler from dropping into the groove during its revolution.

4. A spinning mechanism comprising a spinning ring and a traveler having opposed cooperating surfaces between which the yarn extends and is pressed and forms a bearing medium during the spinning operation, and means for relieving the bearing pressure on the yarn during a portion of the revolution of the traveler to release the yarn for winding.

5. A spinning ring having a peripheral inner surface against which normally the yarn is pressed and travels during the spinning operation and having a depression in the said surface for relieving the pressure on the yarn when it travels thereover and thus release the yarn for winding.

6. A spinning ring having the construction defined in claim 5, in which the said depression is in the form of a groove extending across the said surface at an inclination to the elements thereof.

7. A spinning ring having the construction defined in claim 5, in which the said depression is in the form of a groove extending across the said surface at an inclination both to the elements thereof and to the plane of a traveler when running thereon.

8. A spinning mechanism comprising a spinning ring, the inner periphery of which comprises upper and lower inwardly converging bearing surfaces, a traveler shaped so that, when it is running with its inner horn riding on the said lower bearing surface, the yarn will extend, be pressed, and form a bearing medium, between the inner side of the adjacent bow section of the traveler and the upper bearing surface of the ring, and means for releasing the bearing pressure on the yarn during a portion of each revolution of the traveler to release the yarn for winding.
9. A spinning mechanism comprising a spinning ring, the inner periphery of which comprises upper and lower inwardly converging bearing surfaces, a traveler shaped so that, when it is running with its inner horn riding on the said lower bearing surface, the yarn will extend, be pressed, and form a bearing medium, between the inner side of the adjacent bow section of the traveler and the upper bearing surface of the ring, and a depression in the upper bearing surface of the ring for relieving the pressure on the yarn when the traveler passes thereover and thus release the yarn for winding.
10. A spinning mechanism comprising a spinning ring, the inner periphery of which comprises upper and lower inwardly converging bearing surfaces, a traveler shaped so that, when it is running with its inner horn riding on the said lower bearing surface, the yarn will extend, be pressed, and form a bearing medium, between the inner side of the adjacent bow section of the traveler and the upper bearing surface of the ring, and a groove extending across the upper bearing surface of the ring at an inclination to the elements thereof and at an inclination to the plane of the traveler when running thus to relieve the pressure on the yarn when the traveler passes over the groove and release the yarn for winding.
11. A spinning mechanism comprising a spinning ring, the inner periphery of which comprises upper and lower inwardly converging bearing surfaces, the upper surface being convex, a traveler having its inner horn and the adjacent bow section presenting the same angular relation as the said surfaces, the draft on the yarn and the centrifugal force generated by the revolution of the traveler acting to cause the traveler to run with its inner horn riding on the said lower

bearing surface of the ring and with the inner side of the adjacent bow section extending substantially equidistant from and close to said upper bearing surface with the yarn extending, pressed, and forming a bearing medium therebetween, and means for relieving the bearing pressure on the yarn during a portion of each revolution of the traveler to release the yarn for winding.

12. A spinning mechanism comprising a spinning ring, the inner periphery of which comprises upper and lower inwardly converging bearing surfaces, the upper surface being convex, a traveler having its inner horn and the adjacent bow section presenting the same angular relation as the said surfaces, the draft on the yarn and the centrifugal force generated by the revolution of the traveler acting to cause the traveler to run with its inner horn riding on the said lower bearing surface of the ring and with the inner side of the adjacent bow section extending substantially equidistant from and close to said upper bearing surface with the yarn extending, pressed, and forming a bearing medium therebetween, and a depression in the upper bearing surface of the ring for relieving the pressure on the yarn when the traveler passes thereover and thus release the yarn for winding.

13. A spinning mechanism comprising a spinning ring, the inner periphery of which comprises upper and lower inwardly converging bearing surfaces, the upper surface being convex, a traveler having its inner horn and the adjacent bow section presenting the same angular relation as the said surfaces, the draft on the yarn and the centrifugal force generated by the revolution of the traveler acting to cause the traveler to run with its inner horn riding on the said lower bearing surface of the ring and with the inner side of the adjacent bow section extending substantially equidistant from and close to said upper bearing surface with the yarn extending, pressed, and forming a bearing medium therebetween, and a groove extending across the upper bearing surface of the ring at an inclination to the elements thereof and at an inclination to the plane of the traveler when running thus to relieve the pressure on the yarn when the traveler passes over the groove and release the yarn for winding.

In testimony whereof, I have signed my name to this specification.
